STEAM-POWER PLANT

Application filed March 1, 1926. Serial No. 91,342.

This invention relates to steam power plants, such, for example, as include a steam generator and high pressure and low pressure prime movers, such as turbines.

5 The invention has for its primary object improvements in the reheating of steam. The nature and advantages of the invention will become clear in the following specification of the best embodiment of my invention now 10 known to me.

The preferred form of my invention is illustrated in the accompanying drawings, wherein—

Fig. 1 is a diagrammatic view partly in 15 section and partly in side elevation illustrating my invention,

Figs. 2 and 3 are similar views illustrating modifications of the invention, and

Fig. 4 is an enlarged fragmentary view, 20 partially in section, of certain of the details of Fig. 2.

Referring now to Fig. 1, the reference letter A indicates the furnace of any suitable form of steam generator B, preferably a high 25 pressure generator. The reference letter C indicates a high pressure prime mover, such as a turbine, and the reference letter D indicates a low pressure prime mover, such as a turbine.

30 Beyond the boiler B is a superheater 7 which supplies steam to the high pressure turbine C, as by means of the pipe 8. The exhaust of the high pressure turbine is led through any suitable form of heat interchanger 9 by means of the pipe 10, the reheated exhaust steam being led to the low pressure turbine D after being reheated in the heat interchanger 9.

As a medium for heating the exhaust steam 40 I pass steam from the boiler through a valve controlled pipe 14 to the reheat 9, from whence it passes through pipe 13 to the superheater 11 and then through valve controlled pipe 12 and pipe 8 to the high pressure turbine C. In this arrangement it will be seen that the high pressure steam from the superheater 7 mixes with the superheated, reheated steam flowing from the pipe 12 into pipe 8.

45 By virtue of the difference in temperature and pressure as between the steam to be re-

heated and the steam used to reheat, a very effective transfer of heat is secured, and all special forms of reheating apparatus, such as employ their own source of heat, are avoided.

55 Referring now to Fig. 2, the arrangement is in all substantial respects similar. In this case, however, steam from the superheater 7 branches, part going to the high pressure engine E by the branch 15 and part going to the heat interchanger 9 by way of the branch 16, where it is utilized to reheat the exhaust from the high pressure prime mover which is led to the heat interchanger by the pipe 17. After imparting heat to the exhaust steam, the 60 steam led to the interchanger by the pipe 16 returns to the second superheater 11 by way of the pipe 18, and the steam, after being superheated in this superheater, joins with the steam passing from the superheater 7 to the branch 15 through the medium of the valve controlled pipe 19. The device 22, including the valves 20 and 21 is for regulating the relative amounts of steam which can flow from the superheater 7 to the reheat 9 and to the engine E. These valves are adapted to be shifted by means of a control magnet in turn governed by the thermostat 23 in the line which carries the reheated exhaust steam to the low pressure prime mover F. The temperature of the reheated steam thus governs the valves and adjusts a flow through the respective branches, so as to secure a distribution which will ensure uniform heating.

70 On reference to Figure 4 it will be seen that the valve 20 is normally only partly open and the valve 21 is normally full open. When the temperature of the steam rises sufficiently to cause the device 23 to operate to close the circuit, the solenoid is operated to partially close the valve 21 and to move the valve 20 toward full open position, in consequence of which the flow of steam from the superheater 7 is proportioned between the pipes 15 and 16, less steam going through the pipe 15 than through the pipe 16 when the solenoid has operated as just described. Since this operation means that more steam from the superheater 11 will pass through the pipe 15 than before, the temperature of the exhaust in line 75 80 85 90 95 100

17 will be lower because of the fact that the superheater 11 follows the superheater 7 and therefore does not have the steam passing therethrough superheated to as high a degree as the steam passing through the superheater 7.

10 In the arrangement of Fig. 3, three prime movers G, H and I of different pressures are provided, and steam from the superheater 7 is first led to an interchanger 9^a, where it is utilized to reheat the exhaust from the prime mover G, after which it is led to another heat interchanger 9^b where it is used to reheat the steam from the second prime mover 15 H, the steam thereupon being led to the superheater 11 where it is superheated and delivered to the high pressure prime mover G.

What I claim is:—

20 1. In combination, a boiler, a superheater, a high pressure engine, a pipe leading from the superheater to the high pressure engine, a low pressure engine, a reheater between the engines, a pipe leading from the boiler to the reheater for supplying steam for reheating 25 the exhaust from the high pressure engine, a second superheater, a pipe leading from the reheater thereto, and a pipe leading from such superheater to join with the pipe leading from the first superheater to the high pressure engine.

25 2. In combination, a boiler, a superheater, an engine, a pipe leading from the superheater to the engine, a second pipe in parallel with the first pipe and conducting steam from said superheater to an exhaust steam re-heater, such re-heater, and means for proportioning the flow through said pipes, together with a second superheater, a pipe leading thereto from the re-heater, and a pipe leading 30 from such superheater to join with the pipe leading from the first superheater to the engine.

In testimony whereof I have hereunto signed my name.

EDWIN A. PACKARD.
